SPACE-DISCHARGE SYSTEM

Application filed December 31, 1934. Serial No. 758,988.

This invention relates to space discharge systems and more particularly to a balanced input circuit for systems including three-electrode devices of the type adapted for use 5 as repeaters or amplifiers.

As is well known, when system including space discharge devices are operated so that the grids or control electrodes of the discharge devices are positively charged during 10 successive positive half cycles of the impressed wave, the corresponding half cycles of the output wave are considerably distorted. This is due in part to the fact that the circuit, through which the wave is impressed upon the input electrodes of the discharge device, includes impedance when the positive half cycle of the wave to be repeated is impressed upon the input circuit. When the positive half cycle is applied across the 15 grid and cathode grid current flows, with the result that the E. M. F. effective across the input electrodes is reduced. On the other hand, when the negative half cycle of the wave is impressed upon the input electrodes, 20 no grid current flows and the E. M. F. impressed upon the input electrodes is the full voltage of the source. Under these conditions, the two half cycles of the output wave 25 are different from each other.

In order to overcome this disadvantage, it has been the practice heretofore to impress the wave to be repeated on the input electrodes of the devices through a circuit provided with means for limiting variations in 30 its impedance. This has been accomplished by connecting in parallel with the circuit coupling the wave source to the system, and hence in parallel with the input electrodes of the device or devices, a resistance or other 35 impedance element which is continuously conductive for the impressed wave. For both half cycles of the impressed wave, variations in impedance of the input circuit are limited by the shunt conductive element, and 40 a current flows through and is dissipated in this element with the result that its use represents a waste of energy.

The symmetry of the output wave will be 45 improved by using a shunting element, the impedance of which is small compared with

the grid-cathode impedance of the repeater when its grid is positive. This method, however, may require the use of a shunting resistance so low that a very large amount of energy is dissipated in the resistance, and a 55 large part of the E. M. F. is absorbed in the impedance of the line or wave source.

As a compromise, it has been, in general, the practice to employ a shunt element, the impedance of which is equal to one half the 60 grid-cathode impedance of the repeater when its grid is positive. With the ordinary impedance in the wave source, the conductance of the shunt element is not sufficient to eliminate distortion of the impressed wave and, as 65 a result, the repeated wave is unsymmetrically distorted. Thus, the use of a continuously conductive path while serving to reduce the dissymmetry of the repeated wave, 70 achieves this result only with the expenditure of an excessive loss of power.

The present invention provides a balanced input circuit, the impedance of which for both half cycles of the impressed wave is 75 equal to that of the space path between the input electrodes of the discharge devices, whereby the input circuit losses are materially reduced and both half cycles of the wave 80 are distorted to the same extent.

In accordance with this invention, a two 85 electrode space discharge device having the same impedance characteristics as the three-electrode space discharge repeating device is connected in shunt to the input circuit of the repeater. The filament of the two-electrode device is connected to the grid of the repeater and its plate is connected to the filament of the repeater.

The arrangement described above, sets 90 forth briefly and in a general way one embodiment employing the principles of the invention. However, this description is not to be construed as limiting the scope of the invention. The various combinations and features of the invention which are believed 95 to be novel will be defined in the attached claims.

One object of this invention is to reduce the power losses in space discharge repeating 100 systems.

A feature of the invention is the provision of a balanced input circuit for power amplifiers, whereby the amplifying system may be operated at high efficiency.

For a complete understanding of this invention, both as to its organization and method of operation, reference should be made to the following specification read in conjunction with the attached drawing in which the invention is illustrated, by way of example, as applied to an amplifier included in a high power radio telephone system. Figs. 1 and 2 show different circuit arrangements embodying the invention.

Referring now to Fig. 1, there is shown a circuit 1 adapted to supply a carrier wave modulated in accordance with speech currents. The modulated wave is transmitted by the transformer 2 to the input circuit of an amplified A, shown by way of example as comprising two parallel connected space discharge devices 3, each including a cathode, an anode and a grid or control electrode.

Current for heating the cathodes of devices 3 is supplied by the alternating current source 4 through the transformer 5. The terminals of the parallel connected cathodes are connected to the terminals of the secondary of the transformer 5 and the midpoint of this winding is connected to the conductor 6 which is grounded at 7.

Space current is supplied to the devices 3 from the source 8 over the following circuit: From the positive terminal of the source 8, choke coil 9, anodes of the devices to their cathodes, secondary of transformer 5, conductor 6, to the other terminal of source 8.

Alternating current output energy from the devices 3 flows through the condenser 10, the closed loop, including the inductances 11 and 12 shunted by the condenser 13 in series with the condenser 14; conductor 6, condensers 5^a in shunt to the secondary winding of transformer 5, to the cathodes of devices 3 and across the space within them to their anodes. The condensers 5^a provide low impedance paths for high frequency current.

The path comprising the closed loop 11, 12 and 13 in series with the condenser 14 is also included in the input circuit of the high power amplifier A_p. This path, therefore, constitutes a coupling circuit, whereby the amplified wave supplied by the devices 3 is impressed upon the input electrodes of the high power amplifier A_p.

The amplifier A_p is shown as comprising three parallel connected three-electrode space discharge devices 15.

The cathodes of the devices 15 are connected in parallel across a circuit 16 connected to the terminals of the secondary winding of a transformer 17. The midpoint of this winding is connected to the conductor 6. The primary winding of transformer 17 is connected to an alternating current source 18, which

supplies heating current to the cathodes. Obviously, heating current for the filaments of the devices 15 could be supplied by the source 4, through the transformer 5.

Space current is supplied to the devices 15 by the source 8 over the following circuit. From the positive terminal of the source 8, choke coil 19 to the anodes, across the space within the devices 15 to their cathodes, secondary of transformer 17, and conductor 6 to the negative terminal of source 8.

The high power modulated wave flows through the following circuit: from the anodes of 15 through condenser 20, tuned circuit consisting of the coil 21 in parallel with the condenser 22, conductor 6, condensers 17^a in shunt to the secondary of transformer 17, to the cathodes of devices 15, and across the space paths within them to their anodes. Condensers 17^a provide a low impedance path for the high frequency wave. Coil 21, inductively associated with the coil 23 included in the antenna circuit, serves to supply the high power modulated wave to the antenna 24 from which it is radiated.

The condensers 10 and 20 function to prevent the flow of continuous current from the source 8 through the alternating current paths associated with the devices 3 and 15.

A direct current source 25 has a resistance 26 connected across its terminals. Associated with the resistance 26 are contacts 27 and 28. One terminal of the resistance 26 is connected to the positive terminal of the source and to ground through conductor 6. Contact 27 serves to control the value of the steady negative potential impressed upon the control electrodes of the devices 3. A blocking condenser 29 is connected between the conductor 6 and the conductor extending from the contact 27.

Contact 28 serves to determine the steady negative potential impressed upon the control electrodes of the devices 15. This potential is impressed across the following path: from the contact 28, through coil 12 to control electrodes of 15 across the space within them to their cathodes, secondary of the transformer 17 and conductor 6 to the positive terminal of the resistance 26.

Coils 9 and 19 are high frequency choke coils which serve to prevent the high frequency energy being short-circuited through the source 8.

Condensers 14 and 29 serve to determine the paths over which are impressed the steady potentials for the control electrodes of devices 3 and 15.

Connected across the input circuit, i. e. in shunt to the coil 12 of the coupling circuit and the input electrodes of the high power amplifier A_p, is a space discharge device 30 including a cathode 31 and anode 32. The cathode 31 is connected to the control electrodes of the devices 15 and the anode 32 is connected to the cathodes of the devices 15.

Heating current is supplied to the cathode 31 by an alternating current source 23 through a transformer 34, the secondary of which is shunted by by-pass condensers of low impedance to the high frequency wave.

The impedance characteristic of the device 30 should be substantially the same as the grid-cathode impedance characteristic of the high power amplifier.

Fig. 2 illustrates a system substantially the same as that shown in Fig. 1 and corresponding elements are identified by the same reference characters in both figures.

The system of Fig. 2 differs from that of Fig. 1 only in that a transformer 35 is used to couple the amplifier A to the high power amplifier A_p , and the anode of the device 30 is connected through the condenser 14 to the conductor 6. The grid polarizing source for the devices 15 is also connected to the anode 32 and hence this anode is negatively polarized with respect to the cathodes of 15 to the same extent as the grids of 15.

The amplified wave flowing through the output circuit of the amplifier A is transferred by the transformer 35 to the input circuit of the amplifier A_p . Connected in shunt to the secondary winding of the transformer 35 and the input electrodes of the amplifier A_p is the two-electrode discharge device 30.

In both the systems illustrated the high power amplifier may consist of a single discharge tube or any number of such tubes connected in parallel.

For the most effective operation, the two-electrode device 30 should have an impedance characteristic corresponding to that of the amplifier A_p . If a single tube is used as a high power amplifier, the internal impedance of the device 30 should be equal to the grid-cathode impedance of the amplifying tube. If a number of discharge tubes are connected in parallel to constitute an amplifying system, for the best operation the device 30 should have an internal impedance equal to the total impedance i. e. the combined grid-cathode impedance of the parallel connected tubes.

The operation of the high power amplifier may be described as follows: When the half cycle of the wave supplied by the amplifier A through the coupling circuit 11-12-13-14 or transformer 35, as the case may be, is such that the anode 32 is negatively polarized relatively to the cathode 31, its impedance will be relatively high. However, the control electrodes of 15 will be positively charged with respect to their cathodes, and the impedance of the amplifier A_p will be changed from normal to a low value. When the half cycle of the amplified wave flowing through the coupling circuit or transformer is so directed that the anode 32 is positive with respect to the cathode 31, the impedance of the device 30 will be changed from the normal

to a low value, while the impedance of the amplifier A_p will be relatively high.

Since the impedance characteristics of the device 30 and amplifier A_p are substantially the same, the change of impedance during both half cycles of an alternating current wave impressed upon the input circuit will be substantially equal. Hence, under operating condition, the variations of the impedance of the input circuit associated with the amplifier A_p will be materially reduced in magnitude and will be the same for both half cycles of the impressed wave. Moreover, the maximum impedance of the input circuit throughout a complete cycle will never be greater than the maximum grid-cathode impedance of the amplifier A_p , when the grid is positive with respect to the cathode.

While the arrangement described above may be used to advantage with any type of repeating system including space discharge devices, it is especially advantageous when employed in systems including high power devices of this type, since the input power losses for a complete cycle of the impressed wave are determined by the current flowing across the grid-cathode path within the device.

The advantages accruing from the arrangement described above, as compared with systems in which an inductive path in shunt to the input circuit of the discharge device is used, will be apparent from the following considerations: In space discharge systems heretofore known, if the grid-cathode path of the discharge device or parallel connected devices has a minimum impedance value of A when the grid is positive, it has been the practice to connect in shunt to the input terminals of the system a resistance of the order of $\frac{A}{2}$.

If it is assumed that the input voltage is the same for both half cycles of the impressed wave, the average power dissipated in the resistance and grid-cathode path is $\frac{5e^2}{2A}$, where e is the effective applied

voltage. Under similar conditions, a system in which a unidirectionally conductive device having an impedance A replaces the shunting resistance, the average power loss throughout a complete cycle of the impressed wave is of the order of $\frac{e^2}{A}$.

Again, in the previously known systems, while the negative half cycle of the output wave is a faithful replica of the wave impressed upon the input circuit, the positive half cycle included components harmonically related to the frequency of the impressed wave which are of large amplitude.

In the present arrangement, as shown in Fig. 1, both half cycles of the output wave would be distorted to about the same extent

and would include a similar number of components, harmonically related to the impressed wave, which are of substantially equal and relatively small amplitude.

5 In the arrangement shown in Fig. 2, the distortion would be slightly less symmetrical, but much more nearly so than in systems employing a resistance in shunt to the input electrodes. Moreover, since the anode 32 is 10 connected to the contact 28, polarizing source 26 will not cause a direct current to flow between the anode 32 and cathode 31 of device 30, as is the case in the arrangement illustrated in Fig. 1.

15 Because of the use of the balanced input circuit described above, the following additional advantages are obtained. A constant impedance is presented to the source supplying the wave to be amplified and a circuit of 20 smaller volt-ampere capacity may be used for coupling the source to the amplifier.

What is claimed is:

25 1. A repeater system comprising a space discharge device, including a control electrode or grid, and a cathode, an input circuit therefor including an impedance which is substantially equal to the grid-cathode impedance of the device when the positive peak of an impressed wave is applied thereto.

30 2. The combination of a space discharge device, including a control electrode or grid and a cathode, and an input circuit therefor the impedance of which for a complete cycle of an impressed wave is substantially equal 35 to the grid-cathode impedance of the device for the positive peak of the impressed wave.

35 3. The combination of a space discharge device including a control electrode or grid and a cathode, and an input circuit therefor comprising balanced impedances, the impedance of said circuit for both half cycles of the impressed wave being substantially equal to the grid-cathode impedance of the device when the positive peak of the impressed wave is applied to said electrode.

40 4. An amplifying system including a plurality of space discharge devices each having a grid and a cathode, an input circuit therefor having for both half-cycles of the impressed wave substantially the same impedance as the combined impedance of the grid-cathode paths of said devices for the positive peak of the impressed wave.

45 5. An amplifying system comprising space discharge devices each including a cathode and a grid, an input circuit therefor, said circuit including means whereby its maximum impedance for an impressed wave is limited to a value corresponding to that resulting from combining the grid-cathode impedances of said devices when the positive peak of the impressed wave is impressed upon said grids.

55 6. An amplifying system comprising a space discharge device having input elec-

trodes, an input circuit connected to said electrodes, and a space discharge device connected in shunt to said electrodes, said device having the same impedance for impressed waves as the amplifier.

70 7. An amplifying system comprising space discharge devices each having a cathode and a grid, an input circuit connected to said electrodes, and a space discharge device connected to said electrodes, said device presenting the same impedance for an impressed wave as the combined grid-cathode impedances of said amplifying devices when said grids are positive.

75 8. An amplifying system including a space discharge device having a grid or control electrode, an input circuit upon which the wave to be amplified is impressed, and in shunt to said circuit a space discharge device of impedance substantially equal to the input impedance of said amplifier when the grid is positive.

80 9. A space discharge amplifier having input electrodes, a circuit connected to said electrodes, and a space discharge device connected in shunt to said circuit to provide a path which is unidirectionally conductive in the opposite sense to the grid-cathode path of the amplifier, the characteristics of said amplifier and said device being substantially the same.

85 10. A space discharge repeater system comprising at least one space discharge repeater circuit having an input circuit of widely varying impedance for positive and negative half waves of an impressed alternating wave to be repeated, and a shunt upon said input circuit having a widely but oppositely varying impedance for said half-waves whereby the total impedance viewed from an input source of waves is made more equal for positive and negative half-waves.

90 In witness whereof, I hereunto subscribe my name this 30th day of December, A. D., 1924.
